E. A. SWEELY

METAL FRAME

Original Filed Oct. 3, 1922

Inventor

Edward A. Sweeny

By Parker Cook.

Attorney

UNITED STATES PATENT OFFICE.

EDWARD A. SWEENEY, OF ALEXANDRIA, VIRGINIA, ASSIGNOR TO THE WINE RAIL-WAY APPLIANCE COMPANY, OF TOLEDO, OHIO, A CORPORATION OF OHIO.

METAL FRAME.

Original application filed October 3, 1922, Serial No. 592,060. Divided and this application filed June 1, 1923. Serial No. 642,818.

To all whom it may concern:

Be it known that EDWARD A. SWEENEY, a citizen of the United States of America, residing at Alexandria, in the county of 5 Arlington and State of Virginia, has invented certain new and useful Improvements in Metal Frames, of which the following is a specification.

My invention relates to new and useful 10 improvements in metal frames which are to be used on matches or the surrounding walls of other forms of opening; the frame being designed to protect the edges of the walls of the opening and to also support a 15 door or cover.

The present invention is a division of an application filed by me on hatch covers and means for supporting and locking the same, filed October 3, 1922, bearing Serial No. 20 592,060.

One of the objects of the present invention is to provide a frame which is relatively light in weight, readily assembled, rigid in construction and relatively cheap 25 to manufacture.

Still another object of the invention is to provide a frame, the parts of which may be interlocked and then riveted to form a substantially unitary structure. Also the 30 ends of certain of the parts of the frame will be slightly offset so that when the frame is assembled, the lower or bearing surface of the frame will be flush throughout.

Still another object of the invention is to 35 provide a frame that may be attached, if desired, to a refrigerator type car roof about a hatch, the frame thus protecting the side walls of the hatch where they project above the level of the car roof and also protect 40 the upper edge or upper surface of these walls.

As is well known, the hatch of a refrigerator car has its walls extending slightly above the level of the car roof and on the 45 insertion of the ice in the hatch, these walls become damaged and splinter, so that the cover of the hatch, when closed, will not form a tight connection therewith.

Referring now to the drawings showing 50 a preferred embodiment of my invention,

Fig. 1 is a top plan view of the hatch frame in its assembled position;

Fig. 2 is an enlarged detail of one of the corners of the frame;

Fig. 3 is a side elevation of the corner of 55 the frame, the latter being tilted for the sake of clearness of illustration.

Fig. 4 is a fragmentary section taken on line 4—4 of Fig. 2 looking in the direction of the arrows; and 60

Fig. 5 is an enlarged detail of a corner similar to Fig. 2 but before the two parts are in their final set position.

Referring now more in detail to the several figures, there is shown the frame 65 which consists of the rear piece 1, and the front piece 2, in which are fitted the side pieces 3 and 4, as will be shortly described. These front and rear pieces each consists of what I term the base or body 5, and may 70 be of any desired weight and thickness, and may be formed of iron, cast steel or malleable iron. The rear piece 1 has formed thereon the brackets 6 for the reception of the hinge pintles, while the front piece 2 75 has a bracket 7 for the reception of a hasp or link, as may be desired. The outer edges of these bases may be rounded at intervals as at 8 to provide a sufficient thickness of metal opposite the bolt or lag screw holes 9. 80 In a like manner, the side pieces 3 and 4 have their bases rounded at points along the edges for a similar purpose.

Referring now to the front piece 2 of the frame, it will be seen that extending nearly 85 its entire length is the upstanding wall 10 which is curved at right angles at its opposite ends as at 11, and extending from the top of this wall inwardly (with relation to Fig. 1), there is provided the flange 12, 90 while from the outer edge a short downwardly extending wall 13 may be provided as shown in dotted lines in Figs. 2, 3 and 5.

As may be seen in Fig. 4, the base of this 95 front piece is slightly offset at its ends, as at 14, so that when the sides 3 and 4 are positioned, as will be shortly mentioned, the side together with the front and rear pieces will present a plane surface throughout their length. The rear piece 1 is also formed with 100 the walls and flanges similar to the front piece just described, as may be clearly seen in Fig. 1.

It is also to be noted that the small downwardly extending wall 13 does not extend 105 the full length of the flange 12, but stops short of its ends as shown by the dotted lines 15.

Referring now to the side pieces 3 and 4, they are likewise provided with an upstanding wall 16 and the inwardly extending flange 17 and the small downwardly extending wall 18, while at the opposite ends of these pieces and extending beyond the ends of the walls 16 are the raised tongues 19 to fit within the sockets formed by the bending of the walls 10 and flanges 12, at their corners as shown at 11, heretofore mentioned. The ends of these side pieces fit against the offset portions of the front and rear pieces, as also previously mentioned, and then are riveted as shown at 20. The walls 10 and flanges 12 register with the walls 16 and flanges 17 when all the parts are in position as will be readily understood from the several figures.

From the foregoing it will be seen that I have provided a frame wherein the four parts substantially interlock after which they will be securely riveted to each other, thereby forming an exceedingly strong and rigid structure.

It will also be seen that if the frame is placed about the walls of a hatch, it will protect it from any damage from its sides while the overhanging flanges will securely protect the upper edges of the walls. Furthermore, it will be seen that the frame is one that may be manufactured and then shipped in a knocked-down condition, and then may be quickly assembled and riveted at its four corners, when desired.

Many slight changes may be made without departing from the spirit and scope of my invention.

Having thus described my invention, what I claim as new and desire to secure by Letters Patent is:—

1. A metal frame comprising front, rear and side pieces, all of which are provided with upstanding walls which register when the frame is assembled, said walls having registering flanges extending inwardly to form a rim, the several walls interlocking in a telescopic manner when the frame is assembled and the said pieces also rigidly secured to each other at their ends.

2. A metal frame comprising front, rear and side pieces all of which are provided with upstanding walls which register when the frame is assembled, said walls having flanges extending inwardly and registering therefrom to form a rim, the walls on the front and rear pieces curved at their oppo-

site ends and these curved portions together with the end portions of the flanges of these pieces forming receptive chambers, the side pieces provided with raised portions 60 at their ends to engage the walls of said receptive chambers to thereby interlock the several parts and the several parts also riveted to each other at their several ends.

3. A frame comprising a front and rear piece, each of said pieces provided with an upstanding wall extending substantially throughout its length, said wall curved at its opposite ends, said wall also provided with an inwardly extending flange, side 70 pieces, each of which is also provided with an upstanding wall and adapted to register with the walls of the front and rear pieces when the frame is assembled, each of the said walls of said side pieces provided with 75 an inwardly extending flange and said side pieces provided with a tongue located beyond the ends of said walls to fit within the curved wall of the front and rear pieces, and the several parts riveted together at the 80 four corners of the frame.

4. A frame comprising front, rear and side pieces, the ends of these front and rear pieces offset on their under surface at their opposite end, and the ends of the 85 side pieces secured to the offset ends to thereby present a flush under surface for the entire frame, each of the several parts of the frame provided with upstanding walls and inwardly extending flanges extending from 90 said walls, all of which register when the frame is assembled, the said side pieces provided with tongues to interlock with the walls of the front and rear pieces, and the several ends of the frame riveted to each 95 other after the frame is assembled.

5. A hatch frame comprising front, rear and side pieces, each of said pieces comprising a base and an upstanding wall at its inner edge and a rim extending from said wall, 100 all of said walls and rims registering when the frame is assembled, raised portions formed on the ends of two of the pieces of the frame to interlock with the other two pieces when the frame is assembled, and the 105 ends of the front and rear portions offset so as to present a plane under surface to the entire frame when the same is assembled and the several pieces riveted to each other at their ends.

In testimony whereof I affix my signature.
EDWARD A. SWEELY.
